(57) **CLAIM**

The ornamental design for a light, as shown and described.

DESCRIPTION

FIG. 1 is a front and right side perspective view of a first embodiment of light, showing my new design in an open position;

FIG. 2 is a front view thereof in a closed position;

FIG. 3 is a right side view thereof in a closed position;

FIG. 4 is a rear view thereof in a closed position;

FIG. 5 is a left side view thereof in a closed position;

FIG. 6 is a top view thereof in a closed position;

FIG. 7 is a bottom view thereof in a closed position;

FIG. 8 is a front and right side perspective view of another embodiment of a light, showing my new design in an open position;

FIG. 9 is a front view thereof in a closed position;

FIG. 10 is a right side view thereof in a closed position;

FIG. 11 is a rear view thereof in a closed position;

FIG. 12 is a left side view thereof in a closed position;

FIG. 13 is a top view thereof in a closed position; and,

FIG. 14 is a bottom view thereof in a closed position.
